ABSTRACT OF THE DISCLOSURE

A rugged receiver part for a plug-and-socket type separable fastener, comprising an annular body member having at its inside a heavy cross pin passing through and anchored to its walls, said member having a transverse bottom wall with a drainage opening, and having at its top a cast cover plate and hinge which are protected against damage by being recessed in the top end of the body member and by being substantially flush with the uppermost outer portions of the top end of said member. The peripheral portions of the cover plate are sturdily supported, and the hinge plate thereof is also strongly supported in addition to these parts being protected by recessing, thereby making for a reliable and breakage-resistant assemblage.

Background

This invention relates to separable fastener devices of the type comprising cooperable plug and socket parts, the latter being commonly termed "receivers"; more particularly the invention relates to the receiver parts of such devices.

Heretofore, many receiver parts consisted of open sockets having internal shoulders, cross pins and the like which were subject to weathering, dirt, corrosion, damage from contact with exterior members or other adverse influences, all tending to render the receiver part inoperative. In cases where openable covers existed, these were often damaged rendering them difficult to open or function as intended. Thus, prior receiver parts were at times not fully reliable, particularly under severe or adverse conditions of use.

Summary

The present invention obviates the above disadvantages and drawbacks of prior receiver parts of fastener devices, and an object of the invention is to provide a novel and improved fastener receiver part having an openable, protective cover extending across the socket thereof, which receiver part is especially sturdy, reliable, and resistant to damage and malfunction. This is accomplished by the provision of a tubular metal body member of heavy wall section, having its outer end recessed at the interior, and by the provision of heavy or thick metal cover and hinge components which set into said recess of the outer body end to be flush therewith and to be protected thereby.

2

Preferably the cover and hinge components are made of castings, with sturdy cooperable portions and relatively heavy sections, said components further being adequately supported by non-yielding backing surfaces to better resist contact with or blows from external objects.

Other objects of the invention are to provide an improved receiver part as above, which is of simple construction, involving relatively few parts so constituted as to be economically fabricated and assembled, thereby to effect a low manufacturing cost; to provide a receiver part in accordance with the foregoing, which is easily and quickly operated even by unskilled personnel and under adverse conditions; and to provide a receiver part as characterized, which is small and compact, relatively light in weight, and adaptable to a variety of uses.

Other features and advantages will hereinafter appear. In the drawings:

FIG. 1 is a top plan view of the closed receiver part of a separable fastener as provided by the invention, said receiver part being mounted in a deck plate. Only a small portion of the deck plate is shown in the figure.

FIG. 2 is a diametric section through the receiver, taken on the line 2—2 of FIG. 1.

FIG. 3 is a bottom plan view of the receiver of FIGS. 1 and 2, per se.

FIG. 4 is a fragmentary section, taken on the line 4—4 of FIG. 1.

FIG. 5 is a top plan view of the hinge plate component of the receiver part.

FIG. 6 is a diametric section of the hinge plate, taken on the line 6—6 of FIG. 5.

FIG. 7 is an axial sectional view of the receiver part in the open condition, and of a cooperable coupling or plug part positioned for insertion in the receiver part.

FIG. 8 is a sectional view of the receiver part and a side elevational view of the coupling part, both still in separated condition, the section being in a plane at 90° to the plane of FIG. 7.

The coupling or plug part illustrated in FIGS. 7 and 8 and designated generally by the numeral 10 is described and claimed in detail in my copending application, Ser. No. 390,617 filed Aug. 19, 1964, and entitled "Releasable Mechanical Coupling." Only a brief description of the structure and operation of this coupling part will be given herein, inasmuch as complete details are available in this identified patent.

The coupling part 10 comprises an outer tubular body member 12 which is rigidly affixed to a strut member 14 and which slidably carries a release collar 16 acted on by a helical compression spring 18. The release collar 16 is coupled, by means of a cross pin 20, to an inner, locking tubular member 22 which is axially or longitudinally slidable in the outer, body member 12. The inner locking member 22 has a pair of straight slots 24 located diametrically opposite each other, and the outer or body member 12 has a pair of diametrically opposite transverse slots 26, said sets of slots being generally registered with each other as illustrated.

The transverse slots 26 are somewhat in the nature of a screw helix groove, and can accommodate a cross pin 28 in an annular receiver member or body 30 when the tubular member 12 is inserted therein and given a slight twist. Such accommodation presupposes no interference with the cross pin 28 on the part of the inner locking member 22, and this can be effected by virtue of such member being held in a retracted position by force exerted from right to left on the release collar 16. The locking member 22 however is shown in the advanced position, wherein the notched portion thereof can also accommodate the cross pin 28 after the latter has been fully inserted in the transverse slots 26. Such condition prevents relative turning movement of the plug body 12 in the receiver 30

whereby the body is locked against removal from the receiver.

Considering the locked, assembled position of the plug 10 in the receiver body 30, it will be understood that retraction of the locking collar 16 from right to left, will retract the locking member 22 and remove the interference or contact with the cross pin 28. Thereupon the plug body 12 can be withdrawn from the receiver body 30, accompanied by the aforementioned slight turning movement. Additional details of the construction and action of the fastener part 10 can be had by referring to the above identified patent.

The receiver part embracing essentially the present invention, comprising the annular body 30 and cross pin 28 are given a general designation herein by the numeral 32.

Considering now FIGS. 1-6 the part 32 is noted to be of especially sturdy construction, as is also a cover means included in said receiver part. Essentially the receiver part 32 comprises the annular body member 30 which is formed of metal, having relatively thick walls which carry the cross pin 28. The pin 28 is likewise of substantial diameter, and passes through the thick and solid walls of the body member 30, being at its ends, welded thereto as indicated at 34, such ends and the welds 34 being located in countersinks 36. Even with the presence of the countersinks 36 an appreciable wall thickness of the body member 30 remains, to carry and confine the cross pin 28 whereby the latter is securely supported with a minimum likelihood of bending or deformation.

In accordance with the present invention, a sturdy and thick-walled, hinged cover plate 38 is provided at the upper end of the annular body member 30 and recessed therein, said cover plate being so constructed and mounted, in conjunction with a cooperable hinge pin, that the likelihood of its damage or deformation under adverse conditions of use is largely obviated.

In accomplishing this, the upper end of the body member 30 is provided with a generally annular recess 40 along its interior edge, providing a stepped interior annular shoulder 42 which faces axially away from the body member 30. Disposed in a portion of the annular recess 42 is a hinge plate 44, having pintle-receiving portions 46 disposed on and backed by said interior annular shoulder 42. Also disposed in a part of the recess 40 is the cover plate 38, resting on and backed by portions of the interior annular shoulder 42 and by additional support means or pad shortly to be described.

The cover plate 38 has a pintle-receiving portion 48 which is aligned with and disposed between the pintle-receiving portions 46 of the hinge plate. A hinge pintle 50 extends through said pintle-receiving portions and pivotally secures the cover plate 38 to the hinge plate 44.

Preferably the cover plate 38 is formed of a metal casting, and the same is true of the hinge plate 44. Referring to FIGS. 5 and 6, the hinge plate 44 is preferably of arcuate configuration, having a crescent-shaped base portion 52 provided with screw holes 54 to receive machine screws 56, 58 which are threaded into the heavy wall section of the annular receiver body member 30 as illustrated in FIG. 2. It will be noted that the base portion 52 of the hinge plate 44 is fully supported by the internal shoulder 42 of the receiver body 30, and that except for the pintle-portions 46 of the hinge plate it is flush with the uppermost outer edge portion 60 of the body 30. Accordingly, a sturdy anchorage is provided for the hinge plate as well as a strong, unyielding backing which effects, in conjunction with the coverage afforded by the raised outer edge portion 60 of the body member, a large measure of protection preventing the likelihood of damage or deformation.

The cast metal cover plate 38 rests on the base portion 52 of the hinge plate, as well as on the internal shoulder 42 of the body member 30. Referring to FIGS. 2 and 4, the body member 30 has a strike pad or block 62 disposed in a deep interior recess 64 located opposite

the hinge plate 44 and communicating with the annular recess 40 in the body member. A fastening screw 66 secures the strike pad 62 in place, and the latter is adapted to engage and support the underside of the cover plate 38 when the plate is in the closed position shown in FIG. 1, thereby to additionally reinforce the said plate.

On each side of the strike pad or block 62, the body member 30 has a pair of spaced-apart deep interior recesses 68 also located remote from the hinge plate 44 and communicating with the annular recess 40. In the spaced-apart recesses 68 spring clips 70 are carried, secured in place by machine screws 72 threaded into the wall of the annular body member 30. The spring clips 70 cooperate with notched detent lugs 74 provided on the underside of the cover plate 38 as clearly seen in FIG. 4, whereby the cover plate is yieldably held in the closed position and may be swung therefrom through a 180° arc to the open position shown by the broken outline in FIG. 2. A clearance flat 76 is provided on the cover plate 38 opposite the hinge portion 48 thereof to enable a sharp tool to be inserted between the cover plate and the upper rim portion 60 of the body member for the purpose of prying open the cover plate when it is desired to accommodate the plug part 10 in the receiver part 32.

25 The body part 30 is shown as mounted in a deck plate 78, and may be secured thereto by a welding fillet 80, as illustrated in FIGS. 2 and 4. The bottom end of the body member 30 may be partially closed by a square or rectangular bottom plate 82 which does not completely close over the bore of the body member, but instead leaves drain openings 84 as clearly seen in FIG. 3.

It will now be understood from the foregoing that I have provided a novel and improved, extremely rugged and sturdy socket-type receiver member or part for a separable fastener device, which part is of relatively simple construction, involving few components that may be economically fabricated and assembled. The receiver part has an openable cover assemblage which is well protected by the body member of the receiver part, said assemblage being also so constructed and organized as to resist damage, breakage, deformation and malfunctioning. The receiver part is relatively small and compact, and is particularly adapted for use under adverse conditions.

45 Variations and modifications may be made within the scope of the claims, and portions of the improvement may be used without others.

I claim:

1. A receiver part for a separable fastener device of the plug-and-socket type, comprising in combination:
  - (a) an annular body member,
  - (b) a cross pin anchored in said body member, wherein the improvement comprises:
  - (c) one end of said body member having an annular recess along its interior edge, providing an interior annular shoulder which is normal to the axis of the body member and which faces axially away from the body member, said body member having at said recess an annular wall facing radially inward,
  - (d) a hinge plate disposed in a part of said recess,
  - (e) said plate having a pintle-receiving portion disposed on and backed by said interior annular shoulder which faces axially, and having an arcuate edge engaged with portions of said annular wall which face radially inward, thereby to nest the hinge plate and provide multiple-direction backing therefor,
  - (f) a cover plate disposed in a part of said recess, said cover plate resting on and being backed by said interior annular shoulder, which is normal to the axis of the body member,
  - (g) said cover plate having a pintle-receiving portion aligned with the pintle-receiving portion of the hinge plate, and

- (h) a hinge pintle passing through said pintle-receiving portions.
- 2. A receiver part as set forth in claim 1, wherein:
  - (a) said hinge plate and cover plate are substantially flush with the end of the body member.
- 3. A receiver part as set forth in claim 1, wherein:
  - (a) said hinge plate has an additional pintle-receiving portion spaced from the first-mentioned pintle-receiving portion,
  - (b) both said portions of the hinge plate being disposed on opposite sides of the pintle-receiving portion of the cover plate.
- 4. A receiver part as set forth in claim 1, wherein:
  - (a) said body member has a pair of spaced-apart deep interior recesses disposed remote from the said hinge plate and communicating with said annular recess,
  - (b) spring clips carried by the body member in the deep interior recesses thereof, and
  - (c) detent lugs on the under side of the cover plate, engageable with said spring clips to yieldably hold the cover plate in the closed position extending across the said one end of the body member.
- 5. A receiver part as set forth in claim 1, wherein:
  - (a) said body member has a deep interior recess disposed opposite the said hinge plate and communicating with said annular recess, and

- (b) a strike pad disposed in said deep recess and cooperable with the cover plate to position the latter, when closed, flush with the end of the body member.
- 6. A receiver part as set forth in claim 1, wherein:
  - (a) said hinge plate has an arcuate base portion disposed in said annular recess and resting on said annular shoulder,
  - (b) said cover plate when in the closed position, in part resting on said base portion of the hinge plate.
